UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

METAL-HEATING FURNACE.

1,311,962.

Specification of Letters Patent. Patented Aug. 5, 1919.

Application filed March 21, 1918. Serial No. 85,734.

To all whom it may concern:

Be it known that I, JEROME R. GEORGE, a citizen of the United States, residing at Worcester, in the county of Worcester and Commonwealth of Massachusetts, have invented a new and useful Improvement in Metal-Heating Furnaces, of which the following is a specification accompanied by drawings forming a part of the same.

10 My present invention relates to that class of metal heating furnaces which are designed for heating ingots or billets preparatory to their reduction by rolling, and it has for its objects, to secure a more uniform 15 heating of the metal, and to provide means for the automatic discharge of the heated metal from the furnace. These objects, among others, I accomplish by the construction and arrangement of parts as herein- 20 after described, the novel features being pointed out in the annexed claims.

Referring to the accompanying drawings, Figure 1 represents a longitudinal central sectional view of a heating furnace embodying my present invention.

25 Fig. 2 is a transverse sectional view on the plane of the broken line 2-2, Fig. 1, the furnace walls being shown in section beyond said line.

30 Similar reference characters refer to similar parts throughout the different figures.

Referring to the drawings, 1 denotes the heating chamber of a furnace embodying my invention, having an opening 2 at one 35 end for the admission of the metal to be heated, said opening being closed by a door 3. The opposite end of the heating chamber is provided with an opening 4 for the delivery of the heated metal, said opening 40 being closed, in the present instance, by a sliding door 5. The heating chamber is provided with a longitudinal track 7 extending from the receiving opening 2 to the delivery opening 4 for the support of the 45 metal to be heated, in the present instance consisting of ingots 6 supported transversely upon the longitudinal track. The longitudinal track may be of any suitable construction which will permit the sliding

movement of the metal thereon, and capable of withstanding the high temperature of the heating chamber.

In the construction shown in the accompanying drawings the longitudinal track 7 consists of a pair of pipes, which are preferably water cooled and supported upon the transverse water cooled pipes 8. The track 7 extends in a substantially horizontal plane from the receiving opening 2 to a point near the delivery opening 4, where the track has a sharp incline, as shown at 9, leading to a lower horizontal level 10. From the level section 10 the track is inclined, as at 11, through the delivery opening and at an inclination which will cause the heated metal placed thereon to slide down by gravity, and be delivered through the delivery opening upon a series of conveyer rolls 12. The metal to be heated is successively pushed from a platform 13 through the receiving opening 2 into the heating chamber of the furnace by means of a reciprocating pusher 14, actuated by a steam or hydraulic cylinder 15 in the usual manner in furnaces of this class. As the pieces of metal are successively fed to the heating chamber they form a continuous row upon the track 7 and the row is advanced a distance equal to the thickness of the entering piece until the sharp incline 9 has been reached. The next 75 advance movement of the row will cause the forward ingot to fall over the incline 9 and be partially rotated in its descent until it rests in the position of the ingot 16, upon the horizontal section 10 of the 80 track. The ingot in this position is not only rotated to bring a new face uppermost, but it is also separated from the row of ingots to provide a space for the introduction of 85 mechanical means for pushing the ingot 90 from the section 10 upon the inclined section 11, where it slides by gravity through the delivery opening 4 into the position indicated at 17 upon the conveyer rolls 12, which are operated by the rotating shaft 95 18 and bevel gears 19 to convey the heated metal to the reducing rolls of the mill.

During the passage of the metal through

the heating chamber 1 heat is applied by any convenient or known means, in the present instance by the introduction of currents of air through the passage 20 and the 5 fuel gas through the passages 21, at the delivery end of the furnace. The products of combustion are taken through a downward flue 22 at the receiving end of the furnace to a stack.

10 The mechanical means for transferring an ingot from the section 10 of the track to the section 11 consists of a rotating shaft 23 having a crank section 24 adapted to swing between the water pipes forming the 15 track 7 and contact with the rear side of the metal in the position 16 to push the same off the section 10 upon the section 11 of the track. The rotating shaft 23 carries upon one of its outer ends a sprocket wheel 25 20 by which the shaft is rotated by an endless chain from any convenient source of power. The crank section 24 of the rotating shaft travels in a circular path 241 in the direction of the arrow 242 beneath the row of 25 ingots 6, but its path of travel is cut by the plane of the section 10 of the track so that the crank section 24 in its rotation will pass beneath the horizontal row of ingots but will contact with the rear side of the 30 isolated ingot 16. The crank section 24 therefore forms a rotating member which in its sweep above the section 10 of the track wipes the ingot 16 on to the incline section 11. This rotating member is effective in 35 pushing the ingot 16 only through a small arc of its travel. During the remainder of its movement the rotating member passes entirely below the track and is only effective in delivering an ingot which has previously 40 been moved by gravity upon the section 10 of the track, resulting from the admission of a new ingot at the receiving end of the furnace. The rotating shaft 23 carries upon one of its outer ends a short arm 26 connected by a link 27 with an arm 28 of 45 greater length than the arm 26 and attached to a rocking shaft 29. The rotation of the shaft 23 will therefore impart a rocking motion to the shaft 29. The shaft 29 carries an arm 30 connected by a link 31 with the sliding door 5. At each rotation of the shaft 23 the sliding door 5 which closes the delivery opening of the furnace will be 50 raised to permit the discharge of an ingot upon the conveyer rolls 12, and the movement of the rocking shaft 29 is so timed with reference to the movement of the crank 24 that the door 5 will be raised during the 55 passage of the heated ingot through the delivery opening.

By properly timing the rotation of the crank 24 and the reciprocating movement of the pusher 14 in introducing a new ingot to the furnace, the relative time during

which an ingot isolated from the row is 65 allowed to rest upon the section 10 of the track can be determined. The amount of heat to which each ingot is subjected may be determined by the regulation of the temperature in the heating chamber and the frequency at which new ingots are introduced to the furnace. The action of the furnace may therefore be rendered automatic 70 through the control of its temperature and by the movement of its charging and delivering mechanisms. The period of dwell of the ingot upon the section 10 of the track 75 accomplishes a more uniform diffusion of heat, for the reason that the partial rotation of the ingot over the incline 9 presents 80 new sides to the incoming currents of gaseous fuel, and by the separation of the ingot from the row of ingots upon the track 7, a free access of the heating medium is secured to all sides of the ingot. By controlling the 85 period of transition through the furnace as well as the temperature of the heating chamber, uniformity of heating is secured and the entire operation of heating is controlled by 90 mechanical means, effecting a great saving in the cost of labor and avoiding the discomfort to workmen incident to manipulation of heated metal in furnaces of this class.

The shaft 23 is preferably vertically adjustable, in the present instance by supporting the shaft in bearings projecting from plates 32 adjustably attached by bolts 33 to plates 331 on the side walls of the furnace. The plates 331 are provided with ribs 332 to 95 support wedges 333 on which the plates 32 rest. One of the plates 32 also serves to close an opening 34 in one of the side walls of the furnace, of sufficient size to allow the crank 24 to be brought into alignment 100 with the opening 34 and inserted into or removed from the furnace. The shaft 23 is hollow throughout its length and is supplied with a current of water therethrough in order to protect it from the intense heat of 105 the furnace. The floor of the furnace is preferably hopper shaped at 35 immediately beneath the sections 9 and 10 of the track, for the purpose of conducting the slag to 110 a slag pit 36 which is loosened by the agitation of the ingots as they are moved over the sections 9 and 10.

I claim,

1. In a furnace of the class described, a heating chamber having a delivery opening, a longitudinal track, means for advancing a continuous row of ingots along said track, a horizontal support for an individual ingot on a lower level than said track, an inclined track leading from said horizontal support 120 to said delivery opening, a door closing the delivery opening, means for moving an ingot 125 from said horizontal support to said inclined

- track, means for opening said door, and means for operatively connecting said door opening means with the means for moving the ingot from said horizontal support to 5 said inclined track.
2. In a furnace of the class described, in combination, a horizontal support for an individual ingot, means for moving an ingot off said support, comprising a shaft journaled beneath said support, arms carried by said shaft, means for rotating said shaft to carry said arms in a circular path cutting the plane of said support at each end of its circular path and contacting with the side 15 of the ingot during the movement of said arms above the plane of the support, whereby the ingot is pushed by a sliding movement off said support.
3. In a furnace of the class described, a stationary support for an individual ingot, means for moving an ingot from said support, comprising a rotatable shaft journaled directly beneath said support and having radial arms, means for imparting a rotative 25 movement to said shaft to move said arms through a circular path cutting the plane of said support, a delivery opening, a door closing said opening, and means for operatively connecting said door with said billet 30 moving means.
4. In a furnace of the class described, the combination with a heating chamber having a delivery opening, of a track for the support of ingots, a stationary support for an individual ingot at a lower level than said track, an inclined track leading from said support to said delivery opening, means for moving an ingot from said support to said inclined track, a door closing said delivery 35 opening, and means for operatively connecting said door with the means for moving an ingot from said support.
5. In a furnace of the class described, the combination with a heating chamber having a delivery opening, of a track for the support of ingots, a stationary support for an individual ingot at a lower level than said track, an inclined track leading from said support to said delivery opening, means 40 for moving an ingot from said support to said inclined track, a vertically sliding door closing the delivery opening, a rocking shaft journaled at the delivery end of the furnace and provided with an arm pivotally connected with said door, and means for operatively connecting said rocking shaft with the means for moving the ingot from said support.
6. In a furnace of the class described, a heating chamber having a delivery opening, a horizontal ingot support spaced from said opening, an inclined track leading from said ingot support to said opening, a shaft journaled beneath said support carrying radial 45 arms passing through the plane of said ingot support as the shaft is rotated, means for imparting a rotative movement to said shaft, vertically adjustable bearings for said shaft, an arm carried by said shaft, a door closing the delivery opening, a rocking shaft journaled above said door, an arm carried on said rocking shaft, a link connecting said arm with the arm on said rotative shaft, and means for operatively connecting said rocking shaft with said door. 50
7. In a furnace of the class described, the combination with a heating chamber having a delivery opening, of a support for a piece of heated metal located within said chamber, an inclined track leading from said support to said delivery opening, means for pushing a heated piece of metal from said support upon said track, comprising a shaft extending transversely across said chamber, means for imparting a rotative movement to said 55 shaft, a door for closing the delivery opening, means for opening said door, and means for operatively connecting said door opening mechanism with said shaft.
8. In a furnace of the class described, the combination with a heating chamber, having a delivery opening, of a support for a piece of metal to be heated located within the chamber, an inclined track leading from said support to the delivery opening, means for transferring a piece of metal from said support to said inclined track, a door closing the delivery opening, a rocking shaft operatively connected with said door, means for actuating said shaft to open said door simultaneously with the movement of a piece of metal upon said inclined track. 60
9. In a furnace of the class described, a heating chamber, a support for an individual ingot, means for moving an ingot from said support, comprising a rotatable shaft journaled in bearings directly beneath said support, radial arms carried by said shaft, and means for imparting a rotative movement to said shaft to carry said arms into contact with an ingot on said support and to move said arms in a circular path to push the ingot off said support. 65
10. In a furnace of the class described, a heating chamber having a delivery opening, a longitudinal track for the support of ingots, a support for an individual ingot on a lower level than said track, an inclined track leading from said support to said delivery opening, means for moving an ingot from said support to said inclined track, and a hopper-shaped recess in the floor of the heating chamber directly beneath said ingot moving means and subtending said support and a portion of said longitudinal track and a portion of said inclined track. 70
11. The combination in a metal heating furnace provided with a delivery opening,

of a door closing said delivery opening, an inclined track leading to said delivery opening over which an ingot is discharged from the furnace by gravity, mechanism for moving an ingot onto said inclined track, mechanism for opening the door of the delivery opening, and means for operatively connecting said door opening mechanism and said

ingot moving mechanism to insure their joint action.

10

Dated this eleventh day of March 1916.
